UNITED STATES PATENT OFFICE.

JOHN RILEY JOHNSON, OF NEW BRIGHTON, PENNSYLVANIA.

SANITARY RAZOR-STROP CABINET.

1,297,568.

Specification of Letters Patent. Patented Mar. 18, 1919.

Application filed November 18, 1918. Serial No. 263,037.

To all whom it may concern:

Be it known that I, JOHN R. JOHNSON, a citizen of the United States, residing at New Brighton, in the county of Beaver and 5 State of Pennsylvania, have invented certain new and useful Improvements in Sanitary Razor-Strop Cabinets; and I do declare the following to be a full, clear, and exact description of the invention, such as 10 will enable others skilled in the art to which it appertains to make and use the same.

My invention has for its object to provide a comparatively simple and inexpensive, yet a highly efficient and in every way desirable 15 cabinet for containing razor strops for barber shops and the like, provision being made for wiping the strop with a damp sponge or the like both when it is withdrawn for use and returned to the cabinet, 20 and other provision being made to disseminate ammonia or other fumes in the cabinet for sterilizing purposes.

With the foregoing in view, the invention resides in the unique construction and arrangement 25 of parts hereinafter fully described and claimed, and illustrated in the accompanying drawings.

Figure 1 is a perspective view of the cabinet. 30 Fig. 2 is a front elevation with the front plate removed.

Fig. 3 is a vertical section cut between the front and back sides of the cabinet, showing certain parts in elevation. 35

Fig. 4 is a vertical section on the plane of the line 4—4 of Fig. 2.

Figs. 5 and 6 are horizontal sections as indicated by the line 5—5 and 6—6 of Fig. 3.

Fig. 7 is a perspective view of one of the 40 sponge pressers and its carrying means.

Fig. 8 is a vertical section of the fume disseminator.

Fig. 9 is a perspective view of a hammock which may be employed for supporting 45 the strop wiping sponge.

In the drawings above briefly described, the numeral 1 designates a vertically elongated metal casing whose front may or may not be provided with a removable section 2 50 slidable vertically upon suitable guides 3 as most clearly seen in Fig. 6. The front section 2, as shown, carries the bottom 4 of the casing while the top of the latter, indicated at 5, is removable. The lower side of the 55 top 5 is provided with a cork plug 6 fitting snugly into the upper end of the casing to

prevent the escape of fumes from the disseminator and to prevent the strop wiping sponges from drying out. By tightening the screws 7, the plug 6 may be compressed so that it will expand laterally for tight engagement with the casing. By any suitable means not shown, the casing 1 is rigidly secured to a wall or other suitable support. 60

The front of the casing is provided with a horizontal slot 8 whose lower edge is formed by the upper end of the removable front section 2, and in rear of this slot, a pair of flanged rollers 9 are mounted. The 70 razor strops 10 pass through the slot 8, over the rollers 9, and depend in the casing 1, the lower ends of said strops being connected to cords 11 which are normally wound upon drums 12 in the lower end of the casing, 75 springs 13 being provided to rotate said drums in a direction to wind said cords. It will thus be seen that the spring wound drums 12 normally serve to retain the strops 10 in the cabinet. By pulling upon the handles 14 of 80 said strops however, they may be withdrawn for use, during which movement the drums 12 are rotated by unwinding of the cords 11, thus placing the springs 13 under tension which is utilized in returning the strops 85 into the casing when their use is no longer desired.

Immediately above the rollers 9, strop wipers, preferably in the form of sponges 15, are mounted in any preferred manner. 90 Spurs 16 and rods 17 are shown for this purpose. The rods 17 pass through the sponges and at one end are slidable on vertical rods 18, while their other ends are received in vertical guides 19. By this arrangement, the sponges may be quickly and easily removed when required. 95

Several of the spurs 16 are carried by vertical plates 20 having hooks 21 engaged with rods 21' secured to the back of the casing 1, vertically sliding latches 22 being by preference provided to prevent release of the hooks as shown in Figs. 4, 5 and 7. Sponge pressers 23 rest on the sponges 15 and at 24 are pivotally connected to the upper ends of the plates 20 each of said pressers being preferably of open mesh material such as woven wire, suitable reinforcing frames 25 being provided therefor. Cylindrical necks 26 preferably rise from the pressers 23 and it is by pouring any preferred liquid 100 through these necks that the sponges 15 may 105

be saturated without removing them, it being intended that upon each inward and outward movement of either strop its respective sponge shall wipe, cleanse and dampen 5 its active face, keeping it clean, sanitary, smooth and velvety. However, to prevent the strops from absorbing moisture from the sponges when said strops are confined in the casing as seen in Fig. 4, they are preferably 10 provided with plates 27 of metal or other non-absorbing material, upon which the sponges normally rest. The plates 27 form sliding bottoms for the sponge boxes and may be connected to the strops and handles in 15 any desired way. Also, these plates may be of metal, rubber, or any other appropriate material.

Wires or the like 28 depend from the front ends of the frames 25 and are connected 20 to cross arms 29, and springs 30 are connected to said cross arms, the lower ends of said springs being provided with sheaves 31 over which cords 32 are trained. One end of each cord 32 is anchored to a bar 25 32' in the casing while the other ends of said cords are connected to the drums 12 as seen clearly in Figs. 3 and 4. By the provision of the parts 28 to 32, an elastic connection is established between the drums 12 30 and the pressers 23 and it thus follows that when these drums are rotated by withdrawal of the razor strops, the cords 32 are wound, thus placing the aforesaid elastic connections under tension, so that the sponges 15 35 are yieldably forced against the strops, thus effectively cleansing their active surfaces, both when withdrawing the strops from and returning them to the casing.

To sterilize the strops, a fume disseminator is supported in the casing preferably 40 by means of a wire basket 33. The disseminator shown (see Fig. 8) consists of a bottle 34 to contain ammonia or the like 35, the bottom 36 of the bottle being provided with 45 a small opening 37 closed by a cork 38 bearing against said bottom. A second cork 39 is provided to close the filling neck 40 of the bottle 34, and a rod 41 extends through the cork 38, the opening 36, the bottle 34, and 50 the cork 39, the upper end of said rod being provided with a nut 42, tightening of which will permit more or less forcible contact of the cork 38 with the bottle bottom. A wick 43 is located in the bottle 34 and connected 55 to the rod 41, being preferably wrapped around the latter. The lower end of wick 43 passes through the opening 37 and is clamped between the cork 38 and the bottom of the bottle, and at 44 is wrapped 60 around the cork 38. Cork 38 is provided with a groove to receive the wick 43. The liquid 35 follows the wick by capillarity to disseminate sufficient fumes in the casing to sterilize the strops and sponges. The lower 65 end of rod 41 preferably carries a cage 45

for the cork 38 and the portion of the wick wound thereon. If desired, granules of fume exuding compound may be placed in basket 33.

From the foregoing, taken in connection 70 with the accompanying drawings, it will be obvious that although my invention is of comparatively simple and inexpensive nature, it will be highly efficient and in every way desirable, tending to prevent spread 75 of diseases. It will be noted that since the strops are thoroughly wiped, cleaned, moistened and sterilized, each razor is similarly sterilized by the stropping operation before its use, this being highly important. Also, 80 since the strop is clean, velvety and sanitary, the razor will not cause burning of the face. Since probably the best results are obtained from the details shown and described they may well be followed, but without 85 in the scope of the invention as claimed, numerous changes in form, proportion and minor details may well be made. For instance, instead of the spurs 16 for supporting the pressers, hammocks such as indicated 90 at 50 in Fig. 9 may be used, such hammocks being by preference formed of silk mesh upon wire frames. These hammocks may also be used in connection with the spurs in case the latter should so disintegrate the 95 sponges as to ineffectively support them.

I have shown two strops and a corresponding number of sponges, etc., but it is to be understood that any desired number could well be used.

100 I claim:

1. A razor strop cabinet comprising a casing having a slot, a razor strop normally confined in said casing and adapted to be withdrawn through said slot, a strop wiper 105 in said casing, and means for automatically forcing said wiper against said strop as the latter is withdrawn from the casing.

2. A razor strop cabinet comprising a casing having a slot, a razor strop passing 110 through said slot, a drum in said casing rotated by withdrawal of said strop, a strop wiper in said casing, a presser for forcing said wiper against the strop, and elastic means connecting said drum and presser for 115 operating the latter when said drum is rotated, said connecting means including a flexible element to be wound upon said drum.

3. A razor strop cabinet comprising a casing having a slot, a razor strop passing 120 through said slot, a drum in said casing rotated by withdrawal of said strop, a strop wiper in said casing, a presser for forcing said wiper against the strop, a sheave, spring means connecting said sheave and said 125 presser, and a cord trained around said sheave, one end of said cord being anchored in the casing and the other end thereof being secured to said drum, whereby rotation of said drum by withdrawal of said strop 130

will wind said cord and place said spring means under tension to operate said presser.

4. A razor strop cabinet comprising a casing having in its front a slot, a roller in said casing in rear of said slot, a razor strop passing through said slot and over said roller, a strop wiping sponge in said casing resting on the roller engaging portion of said strop, a sponge presser mounted pivotally in 10 said casing and bearing on the upper side of said sponge, means for moving said strop into the casing including a drum in the lower end of the latter rotated by withdrawal of said strop, and elastic connecting 15 means depending from said pivoted presser and including a cord secured to said drum for winding thereon when the latter is rotated by withdrawal of the strop.

5. In a razor strop cabinet, a casing having a slot, a roller in said casing in rear of 20 said slot, a razor strop passing over said roller and through said slot, means for drawing said strop into the casing, a strop wiper bearing against the roller engaging portion

of said strop, and means for pressing said wiper more tightly against said strop as the latter is withdrawn from the casing.

6. A structure as specified in claim 5, said strop having a non-absorbent portion disposed normally between said wiper and said 30 roller.

7. A razor strop cabinet comprising a casing having in its front a slot, a roller in said casing in rear of said slot, a razor strop passing through said slot and over said 35 roller, a horizontal rod in said casing near its rear side and above said roller, a vertical plate having on its lower end a hook detachably engaged with said rod, a sponge resting on said strop in front of said plate, a 40 sponge presser movably mounted on said plate and resting on said sponge, and means connected to said presser for depressing the latter when said strop is withdrawn.

In testimony whereof I have hereunto set 45 my hand.

JOHN RILEY JOHNSON.
